COMPOSITE PISTON AND METHOD FOR
MAKING SAMEMacy O. Teetor, Newcastle, Ind., assignor to The
Perfect Circle Company, Hagerstown, Indiana,
a corporation of Indiana

Application August 24, 1932, Serial No. 630,180

5 Claims. (Cl. 29—156.5)

This invention relates to pistons and the like and more particularly to composite pistons for internal combustion engines and the like.

The principal object of my invention is to provide a piston having a head and a skirt in constant axial alignment with the connecting means so arranged that the head expands freely without distorting the skirt which is fitted in the cylinder with minimum clearance.

16 More specifically, I provide a piston having a head formed of light material, such as aluminum alloy, and a closely fitting skirt of harder material and having a lesser coefficient of expansion, such as cast iron, and provide struts for connecting the head and skirt together so that the head may expand freely independently of the skirt while at the same time the head is maintained in proper axial alignment with respect to the skirt during operation.

20 A further object of my invention is to provide a novel method of casting such a piston. According to my method the aluminum head is first cast on to suitable struts having the desired coefficient of expansion and then the iron skirt is cast on to the struts. Further the skirt is cast out of round to provide for shrinkage in the iron, the skirt, when finished, being perfectly circular with the walls of proper thickness.

The above and other objects of my invention 30 will become apparent from the following description taken in conjunction with the accompanying drawings, in which:

Figure 1 is a longitudinal vertical section through a piston embodying one form of my invention;

Fig. 2 is a vertical section taken on the line 2—2 of Fig. 1;

Fig. 3 is a horizontal section taken on the line 3—3 of Fig. 1;

Fig. 4 is a vertical section taken through the casting forming the head before it is machined;

Fig. 5 is a horizontal section corresponding to that of Fig. 3 except that the struts are broken away and the section illustrates the skirt at the 45 time it is cast and before the iron cools, and

Fig. 6 is a fragmentary view showing a portion of the skirt in top plan.

The head 6, when finished, as shown in Figs. 1 and 2, is provided with the usual piston ring groove 7 and has two depending arms or hangers 8, carrying the usual piston pin bosses 9. The head is formed of aluminum alloy or other light material having a relatively high coefficient of expansion.

55 The skirt 11 of the piston is formed of hard metal having a relatively low coefficient of expansion, such as cast iron, and is connected to the hangers 8 of the head by two lower supporting struts 12 and two bracing struts 13.

60 Each supporting strut 12 comprises a flat bar of

metal carrying two tubular anchoring pieces 15. The struts 12 are preferably formed of a wide strip of metal having a low coefficient of expansion which may be the same as, or slightly lower than, that of the skirt. Openings, surrounded by flanges 16, are formed in the central portion of each strut 12 and the tubes 15 are driven into these openings in which they have a tight press fit. Each of the bracing struts 13 is in the form of a narrow strip of metal having the same coefficient of expansion as the struts 12. In fact, the struts 12 and 13, associated with each hanger 8, are preferably formed of one piece of metal and are connected together by the vertical connecting bar 19, the metal at the point of union of the bar and strut being bent at right angles so that the strut 13 lies in a horizontal plane.

In making the piston, the supporting struts 12 and the bracing struts 13 are suitably supported in a sand or permanent mould and the aluminum is then poured into the mould to form the unfinished casting as illustrated in Fig. 4. The inner end of the struts 13 are imbedded in the hangers 8 above the bosses and these ends are bent downwardly and provided with holes 18 to 10 better anchor them in the hangers. The lower ends of the hangers are cast around the centers of the struts 12 and the tubes 15 which firmly anchor the struts 12 in the hangers and prevent 15 any relative movement between them. After the 20 aluminum cools, the skirt is then cast onto the struts in a suitable mould, the skirt having the inner projections 20 which are cast around the outer ends of the struts 13 (Figs. 1 and 6) and the projections 21 (Figs. 1 and 3) which are cast 25 around the ends of the struts 12. The outer ends of the struts 13 and the ends of struts 12 likewise have holes which serve to better anchor them to the skirt. A washer 23 (Fig. 4) of asbestos 30 or other suitable material is placed on the end of the flange of the head casting so that when the skirt is cast the cast iron does not come into contact with the head. After the piston is 35 completely cast it is machined and finished.

In operation of the piston in an engine, the 45 head, due to its greater coefficient of expansion and the higher temperature to which it is subjected, expands to a greater degree than the skirt. During this expanding action, the hangers 8 move 50 apart, and during this movement the hangers, as well as the supporting struts 12 and the bracing struts 13 flex so that this expansion is not transmitted to the skirt proper and the latter is not distorted. The struts 13 maintain the head in axial alignment with the skirt which is desirable 55 for efficient operation of the engine. Further, if the head rocked relative to the skirt the lower ends of the hangers and the ends of the struts 12 would be subjected to shearing strains resulting in loose points of connection or breakage. 60

It will also be evident that the hangers, when heated in operation of the engine, tend to elongate vertically, and in order to accommodate this expansion the struts 13 are formed so that they 5 may flex vertically, as well as horizontally.

I find that it is advantageous to connect the struts 13 to the struts 12, as by the bars 19, so that the vertical flexing of the struts 13 does not affect the skirt. Without such connections when 10 the hangers are elongated the upper movement of the struts 13 would tend to distort the skirt slightly adjacent the projections 20, thus causing "high spots". With the bars 19 this objection is eliminated.

15 I have found that with the above described structure, the skirt may have a constantly close fit in the cylinder without undue distortion and that the head is maintained in proper axial alignment on the skirt, thus eliminating objections to 20 which other pistons are subject.

I have found that, when a cast iron skirt is cast directly on an aluminum head or the hangers thereof, the aluminum will either melt or form an oxide at the points of union with the result 25 that the piston is defective. I have also found that it is necessary to anchor the hangers of an aluminum head at more than one point to the skirt but that when the aluminum hangers of the head are cast on to struts which are already 30 anchored at their ends in the skirt, the subsequent shrinkage of the aluminum is likely to cause excessive distortion and loose joints at the anchorage points as the metal cools.

In my method, I first connect the hangers of 35 the aluminum head to each strut at one point only so that the aluminum has every opportunity to shrink around the struts without cracking or without imposing strains on any other parts of the casting. I then cast the iron skirt on to the ends 40 of the struts and during the shrinkage of the cast iron, the flexibility of the struts prevents undue strains from being placed on the hangers or head.

I have found by actual experience that when 45 the skirt shrinks after casting it would become slightly oval if cast circular and with the wall of uniform thickness. Obviously the skirt, when finished, must be round to fit the cylinder. In order to accomplish this circularity, which is 50 shown in Fig. 3, I cast the skirt slightly oval and with tapering wall thicknesses as illustrated in Fig. 5 and then, upon cooling, the interior of the cylinder becomes circular and machining of the exterior brings this exterior into circularity 55 and into concentricity with the interior. This will be clearer from the following explanation, with particular reference to Fig. 5 which shows a cross section through the skirt as it is in the mould cavity and before cooling of the casting. 60 The inside diameter A, which is at right angles to the struts 12 is slightly larger than the uniform inside diameter of the skirt after it shrinks and the diameter B is slightly smaller. The wall of the skirt casting, as shown in Fig. 5, is thickest 65 at bb and tapers both ways, being thinnest at aa. When the casting cools, each strut 12 tends to fixedly hold the projections 21, in which its ends are imbedded, from moving toward each other, or, as it might be expressed, the struts tend to 70 prevent the skirt from shrinking in the direction of the struts. The arcs cc of the wall, being longer than the arcs dd, tend to straighten out

and the inside diameter on the line A is reduced to the final inside dimension. At the same time the points bb move slightly further apart which increases the diameter on which these points lie so that the inside of the piston becomes circular 5 instead of remaining oval. Of course, as the wall thickness varies the exterior of the skirt is oval after the casting cools, but it is made circular in the machining operation as the most metal is removed where the walls are the thickest and when the skirt is finished it is circular and the inside and outside walls are concentric.

It is understood that the structure and method 10 may be modified without departing from the scope of the invention.

I claim:

1. In a piston, a head having depending hangers, a separate skirt, cross struts flexible only horizontally of the piston and having their central portions connected to the lower ends of said 20 hangers and their opposite ends to the skirt, bracing struts flexible vertically and connected at their inner ends to the upper portions of the hangers and at their outer ends to the skirt and means connecting the bracing and cross struts. 25

2. In a piston, a head having depending hangers, a separate skirt, cross struts formed of flat metal flexible only horizontally of the piston and having their central portions connected to the lower ends of said hangers and their opposite 30 ends to the skirt, and bracing struts formed of flat metal lying in a horizontal plane flexible vertically and connected at their inner ends to the upper portions of the hangers and at their outer ends to the skirt, and bars connecting the 35 cross and bracing struts, each bar and the connected cross strut and bracing strut being formed of one piece of metal.

3. In a piston, a head having depending hangers, a separate skirt, cross struts formed of flat 40 metal flexible only horizontally of the piston and having their central portions connected to the lower ends of said hangers and their opposite ends to the skirt, bracing struts flexible vertically and connected at their inner ends to the 45 upper portions of the hangers and at their outer ends to the skirt, and bars connected at their lower ends to the cross struts and their upper ends to the bracing struts intermediate the ends 50 of the latter.

4. The method of making a piston which consists in placing struts in a mold, casting the head and its hangers so that the hangers are cast around portions of the struts, next casting the skirt out of round on to ends of the struts, then permitting the skirt to shrink, the skirt interior 55 being thereby brought into circularity, and finally finishing the exterior of the piston.

5. The method of making a piston which consists in placing struts having a low coefficient of 60 expansion in a mold, casting the head and its hangers having a high coefficient of expansion so that the hangers are cast around portions of the struts, next casting the skirt out of round and with walls of varying thickness on to ends 65 of the struts, then permitting the skirt to shrink the interior being thereby brought into circularity, and finally finishing the exterior of the skirt to bring the exterior of the skirt into circularity 70 and concentricity with the interior of the skirt. 70
